(57) **CLAIM**

The ornamental design for an iced beverage merchandiser, as shown and described.

DESCRIPTION

A portion of the disclosure of this patent document, including appendices, may contain material which is subject to copyright protection. The copyright owner has no objection to the facsimile reproduction by anyone of the patent document or the patent disclosure, as it appears in the Patent and Trademark Office patent file or records, but otherwise reserves all copyright rights whatsoever.

FIG. 1 is a front perspective view of the iced beverage merchandiser showing my new design;

FIG. 2 is a rear perspective view thereof;

FIG. 3 is an exploded view thereof shown with environment;

FIG. 4 is a right side elevational view thereof;

FIG. 5 is a left side elevational view thereof;

FIG. 6 is a front elevational view thereof;

FIG. 7 is a rear elevational view thereof;

FIG. 8 is a top plan view thereof; and,

FIG. 9 is a bottom plan view thereof.

The broken lines showing shelving, wheels, and beverage cases are for the purpose of illustrating the environment of the article only and form no part of the claimed design.
